UNITED STATES PATENT OFFICE

GEORGE LOOP MOORE AND JAMES ROBERT STEELE, OF OWEGO, NEW YORK

RAIL ANCHOR

Application filed October 8, 1931. Serial No. 567,608.

Our invention relates to rail anchors and particularly to anchors for resisting the longitudinal creeping of railroad rails.

One of the objects of our invention is to provide a one-piece anchor which is easily applied to a rail, which efficiently grips the rail base flange and which cooperates with a stationary member of the roadbed to resist the creeping of the rail.

Another object of our invention is to provide a rail anchor which is applied to a railroad rail by distortion and which effectively grips the rail base flange due to the tendency of the anchor to resume the condition from which it was distorted when applied to the rail.

A further object of our invention is to provide a one-piece rail anchor which is adaptable to rails having base flanges of different widths.

Another object of our invention is to provide a rail anchor which will check the longitudinal creeping of the rail in either direction of traffic.

The novel features of our invention will be more fully understood from the following description and claims taken with the drawing in which:

Fig. 1 is a top view of a portion of a railway track structure embodying our improved rail anchor;

Fig. 2 is a side view of the structure shown in Fig. 1;

Fig. 3 shows one end of the anchor applied to a rail flange; and

Fig. 4 shows the other end of the anchor applied to a rail flange.

Referring to the drawing: 14 designates a rail, 15 a cross tie, 17 a railroad spike and 18 the rail anchor which is the subject of our invention.

The anchor 18 comprises end members 19 and 20, respectively, and a connecting member 21 which is adapted to bridge a railroad tie.

The anchor is preferably made from a bar of metal of uniform section and its ends 19 and 20 are formed with upper and lower rail engaging members or jaws 22 and 23, and 24 and 25, respectively, which are adapted to grip one of the flanges of a rail base. The connecting member 21 is preferably provided with a loop portion 26 which is adapted to pass around the toe portion of the head of a railroad spike to prevent lateral displacement of the anchor when it is in its operative position on the rail. The loop portion 26 also functions to engage the sides of the spike head upon the tendency of the rail to creep longitudinally in either direction of traffic so as to retain the anchor in its operative position to resist the creeping of the rail. The connecting member 21, in its normal inoperative condition, is offset from the loop portion 26 towards the end 19 relative to the portion between the loop 26 and the end 20 so that it will be necessary to spring the member 21 downwardly in applying the anchor to a rail so that the anchor will more effectively grip the rail due to the tendency of the member 21 to assume its normal condition.

The anchor is applied to a rail by hooking its end 20 over the flange of the rail so that the jaws 24 and 25 engage the upper and lower surfaces of the flange of the rail base on one side of the tie, passing the loop portion 26 of the connecting member 21 around the spike head 17 and placing the end 19 of the anchor in the position indicated in broken lines in Figs. 1 and 2. Pressure is now applied to the end 19 of the member 21, such as placing the foot thereon and striking a blow downwardly and inwardly at the point indicated by the arrow in Fig. 2. This will cause the jaw portion 23 to pass downwardly beyond the edge of the rail base flange. As soon as the end of the jaw portion passes beyond the flange it will spring inwardly and thus engage the bottom of the

rail base and the jaw 22 will engage the upper surface of the rail base flange. After the anchor has been applied to the rail, the jaws 22 and 23 and 24 and 25, respectively, may be brought more effectively into gripping engagement with the rail base flange by a light blow on the side of the anchor adjacent the jaws.

From the foregoing description it will be obvious to those skilled in the art that we have devised an improved one-piece, two-way anchor which is simple in construction, which is easily applied to the rail base flange, and which efficiently grips same to check the tendency of the rail to creep in either direction of traffic. Our device is particularly adaptable to rails having base flanges of different widths, as it grips only one side of the flange of a rail and therefore its gripping ability is not affected by the changes in widths of base flanges.

Another feature of importance is the fact that our anchor does not depend on any member of the roadbed for its gripping effect on the rail.

While we have shown our invention in but one form it will be obvious to those skilled in the art that it is not so limited, but is susceptible of various other changes and modifications without departing from the spirit thereof, and we desire, therefore, that only such limitations shall be placed thereupon as are imposed by the prior art or as are specifically set forth in the appended claims.

Having thus described our invention what we claim as new and desire to secure by Letters Patent is:

1. A rail anchor comprising rail engaging end members and a connecting member having a loop formed therein to project toward the web of a rail and to pass around a spike head.

2. A rail anchor comprising spaced rail engaging end members, and a connecting member adapted to bridge a tie, said connecting member having a loop portion to project toward the web of a rail and to pass around a spike head.

3. A rail anchor comprising rail engaging end members, a connecting member integral with said end members, said connecting member comprising a loop portion to project toward the web of a rail and to pass around a spike head and a portion adjacent said loop portion adapted to grip the rail flange.

4. A rail anchor comprising rail engaging end members, a connecting member for said end members, said connecting member having a loop portion to project toward the web of a rail and to pass around a spike head and a portion adjacent said loop portion adapted to be distorted during the application of the anchor to a rail.

5. A rail anchor comprising spaced end members having jaws adapted to grip one

flange of a rail base on opposite sides of a railroad tie, a connecting member for said end members and means associated with said connecting members adapted to pass around a spike head in a plane substantially at right angles to its axis.

6. A rail anchor comprising a member adapted to bridge a railroad tie and engage the upper surface of the flange of a rail, a member at each end thereof for engaging the lower surface of the rail base flange, and a loop formed in the first mentioned member for engaging the end of the toe portion of a spike head.

7. A rail anchor comprising a member adapted to bridge a tie, end members having jaws adapted to grip a rail base flange and means integral with the first-mentioned member adapted to engage the toe portion of a railroad spike to resist longitudinal movement of the anchor.

8. A rail anchor comprising end members having jaws adapted to grip one flange of a rail and a connecting member having a loop portion adapted to engage the end of the toe portion of a spike head to retain the anchor in operative position on the rail.

9. A one piece rail anchor comprising jaw members adapted to grip a rail flange at opposite sides of a tie and a member connecting said jaw members, said member having a loop portion to pass around the head of a railroad spike in a plane substantially parallel to the upper surface of the rail flange and provide a fulcrum for the anchor.

10. A rail anchor comprising a bar of substantially uniform cross section having a portion bridging a railroad tie, outwardly extending end portions integral with said portion adapted to engage the upper surface of a rail base, said end portions having their extremities bent downwardly and inwardly towards said first mentioned portion to provide jaws for engaging the under surface of a rail base flange.

11. A rail anchor comprising a bar of substantially uniform cross section having a portion bridging a railroad tie, said portion being deformed to loop about the longitudinal axis of a spike and engage the spike head, and outwardly extending end portions integral with said portion adapted to engage the upper surface of a rail base, said end portions having their extremities bent downwardly and inwardly towards said first mentioned portion to provide jaws for engaging the under surface of a rail base flange.

12. A rail anchor substantially uniform in cross section comprising end members adapted to engage the upper and lower surfaces of a rail base flange on opposite sides of a railroad tie, a connecting member for said end members, said connecting member comprising a loop portion adapted to receive a spike head, a curved portion intermediate

said loop portion and one end of the anchor and a portion deflecting upwardly from said loop portion towards the other end of the anchor.

5 13. A rail anchor substantially uniform in cross section comprising a member adapted to bridge a tie, said member comprising a loop portion adapted to receive a spike head, and end members extending outwardly, 10 downwardly and inwardly of said connecting member adapted to engage a rail base flange.

In testimony whereof we hereunto affix our signatures.
